UNITED STATES PATENT OFFICE.

EDWIN PYNCHON, OF CHICAGO, ILLINOIS.

ADJUSTABLE CHAIR.

SPECIFICATION forming part of Letters Patent No. 443,197, dated December 23, 1890.

Application filed May 27, 1886. Serial No. 203,468. (No model.)

To all whom it may concern:

Be it known that I, EDWIN PYNCHON, a citizen of the United States, residing at Chicago, in the county of Cook and State of Illinois, have invented a new and useful Improvement 5 in Adjustable Chairs, of which the following is a specification.

My invention relates to adjustable chairs, particularly such as are used by physicians. 10 The object of my invention is to provide a chair which shall have an adjustable seat, seat front and back, and a swinging seat front and back. I accomplish this object by the mechanism illustrated in the accompanying 15 drawings, wherein—

Figure 1 is a side view of my chair in its ordinary position. Fig. 2 is the same with seat and seat-frame elevated. Fig. 3 is a vertical section taken through the line X X of Fig. 2, looking rearward. Fig. 4 is a plain section taken through line Y Y of Fig. 2, looking downward. Fig. 5 is a detail of the back-locking device. Fig. 6 is a detail of the tilting-frame-locking device. Fig. 7 is a side 25 view of the chair with back reclining, seat-frame elevated, and stirrups attached. Fig. 8 is a detail of a slightly-modified step. Fig. 9 is a section on a vertical longitudinal section through the middle of the chair. Fig. 10 30 is a detail view.

Like parts are indicated by the same letter in all the figures.

I first describe the side supports of the chair and parts which support the swinging chair.

35 A A are irregular arch-shaped pieces, which form the sides of the chair-frame.

A² A² and A' A' are respectively cross and longitudinal pieces of the frame.

A³ A³ are pivots on the arch; A⁴ A⁴, pivots 40 on the tilting frame, and A⁵ A⁵ hangers which pivotally join the arch and tilting frame. The central hanger is vertical in its ordinary position and the others are at an angle of about forty-five degrees thereto.

45 B is the side bar of the tilting frame, suspended by the hangers and having the downwardly-projecting locking-bar B' rigid therewith.

B² B² are holes in the bar. 50 I now describe the device for elevating the chair on the tilting frame.

B⁴ B⁴ are pivots, which secure the ends of the bars B³ B³ to the inner side bar B¹⁵ of the tilting frame. B⁵ B⁵ are similar bars pivoted at B⁶ B⁶ to the sliding bar B⁷, which is placed 55 so as to longitudinally reciprocate in the groove or recess B⁸ of the bar B¹⁵. The bars B³ B³ and the bars B⁵ B⁵ are pivoted to the side bar C of the seat-frame, as at B¹¹ B¹¹.

D is the sliding frame, composed of the bars 60 D' D' and D², the latter being provided with a screw-hole to receive the screw D³, which is provided with the crank D⁴. The screw is journaled in the box on the rear edge of the box B⁹ and the box D⁶ on the cross-bar B¹⁰. 65 The sliding frame is secured to the sliding bars B⁷ B⁷, so that by turning the screw D³ the frame and bars will slide on the tilting frame.

B⁹ is a forwardly-opening box secured to 70 the lower front part of the tilting frame and seat.

C C are the side bars of the seat-frame, connected at their rear ends by the cross-bar B¹⁰.

C' C' are eyes on the side and front cross- 75 bars of the seat-frame.

C² is a rear cross-bar of the seat-frame. C³ is an intermediate cross-bar of the seat-frame, and C⁴ is the front cross-bar of the same. The side bars C C are channel-bars, 80 and the links B³ and B⁵ are pivoted to the outer and inner flanges, so as to fold into the channel.

E E and E' E' are the bars which form the 85 seat.

E³ E³ and E² E² are pivoted bars, which support the seat from a frame which slides on the seat-frame as the sliding frame just described slides on the tilting frame. E⁴ is such sliding frame, and E⁵ is the screw which 90 moves it.

F' F', F² F², and F F are the pieces which form the back. They are composed of flat metal strips, and the top and bottom ones are bent at the ends and secured so as to open in 95 opposite directions.

At the lower end of the back and on each side thereof is an arc-shaped piece F³, secured thereto and having the holes F⁵.

F¹⁰ is a lug on the inside of the arc-shaped 100 piece at its forward point, adapted to engage the under side of bar C when the back is re-

clining, so as to support the back on opposite sides of the pivot. At the point F⁴ the back is pivoted in front of the rear cross-piece of the seat-frame.

5 F⁶ is a cross-rod in the top and on the rear side of the back and is designed to support a head-rest.

The back-locking device is composed of the laterally-reciprocating rods G G, kept laterally extended by the encircling spiral springs G² G² and supported on the rear cross-piece C² of the seat-frame by the brackets G³ G³. A lever-arm G', pivoted on the brackets C³ and adapted to engage the rods G G, serves 15 to retract them when desired. In their normal positions these rods pass through holes in the side bars of the seat-frame and project through the apertures in the arc-shaped piece F³.

20 H H are rods bent into hooks at the ends and passed through eyes on the elbow-levers H' H'. H² H² are the points at which these elbow-levers are pivoted to the cross-piece A². This cross-piece is turned up at the ends and 25 bolted to the frame, and in the middle it is provided with the supporting-plates H⁹ H⁹, through eyes in the ends of which pass the rods H H. Encircling these rods are spiral springs H³ H³, which keep them normally 30 protruding at the sides where they pass through apertures in the frame and into the holes B² B², thus locking the tilting frame in position. The rod H⁵ passes through eyes in the cross-pieces A² A² and is attached to the 35 free ends of the elbow-levers. It is kept normally elevated by the encircling spiral spring H⁴, and is attached to the swinging cross-lever H⁶, provided with the protruding foot-pieces H⁷ H⁷. By pressing on either of these 40 the lever and rod are drawn down and the elbow-levers moved so as to retract the locking-rods and free the tilting frame.

J is a foot-rest; J', a standard pivoted to the outer edge thereof and designed to support it when in position, and J² J² are lugs thereon, which can be inserted in the eyes C' C' when the foot-rest is to be applied in front or at the side of the seat.

The stirrup or foot and leg rest is composed as follows: The elbow K is provided with the lower rounded part K', which is received into the socket K², where it is free to turn. K⁴ is a second elbow, at the upper end of which is placed the stirrup proper K³. At 55 the point K⁹ the two elbows are pivoted together. A ratchet-bar K⁸ is pivoted to the outer end of the elbow K⁴ and adapted to engage the lug K⁸ on the elbow K, so as to hold the elbow K⁴ in any desired position.

60 K⁶ is a sliding bar, which carries a stirrup K⁵, and is adapted to be locked in any position by the nut and bolt K⁷. K¹⁰ and K¹¹ are arc-shaped pieces, one smaller than the other, both pivoted together, one within the other, 65 at their upper ends, so as to form a cradle-stirrup K⁹. K¹¹ is centrally pivoted to the

bar which supports it, so as to permit of its being turned about.

The use and operation of my invention are as follows: The rod on the rear upper edge 70 of the back is designed to hold a movable head-rest. The rod F⁶, which passes along the upper part of the back, is indicated in Fig. 2. Any kind of a head-rest—as, for instance, one having eyes with set-screws—could 75 be used; but such head-rests are no part of my invention. The rest can be secured by set-screws. The back, being constructed of light metal, can be light and strong. The top cross-piece comes flush with the front surface 80 and the bottom with the rear surface, thus giving the back an easy curve. By moving the lever G' the rods G G are drawn out of the aperture in the arc-shaped plates, and the back can then be swung in either direc- 85 tion to fold up on the seat for shipment or to tilt toward the rear to form a bed. In the latter position the lower end of the back rests on the seat-frame and the lugs on the perforated plates engage the side bars on the seat- 90 frame in front of the pivot, thus giving the back a strong support. The motion of the screws D⁸ or E⁵ serves to move the sliding frames backward or forward, as the case may be, thus extending or contracting the parallel 95 bars and raising or lowering the seat or seat-frame. By pressing on the foot-pieces H⁷ H⁷ by the foot on either side the elbow-levers H' are moved and the transverse rods retracted, so as to loosen the tilting frame and permit 100 the same to be inclined in either direction. The foot-rest can be applied at the front for the feet or at the side when the seat-frame is elevated and the occupant is lying on one side. When the seat-frame retreats in its 105 upward movement, it uncovers the box B⁹, and the same can then be used for a step to enable one to reach the elevated seat. When the seat-frame is down, the fringe on the cushion covers the front of the receptacle and it 110 can be used to hold tools and the foot-rest. The stirrup is set in the socket K², and the upper knee-cradle is supported in suitable position by the ratchet and lug. The foot-cradle is supported by the nut. The knee- 115 cradle can be thrown forward so as to serve as a foot-cradle, if desired.

I am aware of German Patent No. 22,145, and United States, Shoeninger, of August 4, 1874, No. 153,684, "swings;" also United States 120 patent to Vorze, June 28, 1870, No. 104,906, "school furniture," and it is not my purpose to claim any of the things in such patents described.

I claim—

1. In an adjustable chair, the combination of the back, formed as shown, and provided at its lower extremity with perforated arc-shaped pieces rigidly secured to the side pieces of the back, with the seat-frame having a rear cross-piece, the arc pieces provided with lugs at their lower extremities and the 130

back pivoted on the seat-frame concentric with its arc-shaped pieces at a point somewhat forward of the rear cross-bar of the seat-frame, and spring-bars normally extended 5 through the perforations in the arc-shaped pieces, but adapted to be retracted so that when the back reclines it is supported on the rear cross-pieces of the seat-frame and also by means of the lugs on the side bars of the 10 seat-frame, and so that it may be locked in any convenient position.

2. In an adjustable chair, a back composed of strips of metal, the upper and lower cross-pieces being bent at the ends, secured to the 15 side pieces, and turned so that the upper is flush with the front and the lower with the rear of the back.

3. In an adjustable chair, a frame, in combination with an adjustable seat-frame and a 20 receptacle which is covered when the seat-frame is down and when the seat-frame is raised is exposed and can be used for a step.

4. In an adjustable chair, the combination 25 of a stirrup, an elbow-lever pivoted at its angle to the standard on the chair and attached at one end to the stirrup, a ratchet-bar pivoted to the other end of the lever, and a lug on the standard which engages the ratchet-bar and thus adjustably holds the stirrup.

5. In an adjustable chair, a compound stirrup 30 consisting of a knee-cradle, supported as shown, and a foot-stirrup adjustably supported by a set-nut, both stirrups being supported on a standard pivoted on the seat-frame.

6. In an adjustable chair, the combination 35 of a tilting seat-supporting frame with a chair-frame, the former suspended from the latter by three hangers on each side, the central hanger being vertical, the side hangers inclining, as shown, and all three pivoted to both frames.

7. In an adjustable chair, the combination 40 of a tilting seat-supporting frame, a seat-frame proper, a grooved bar secured to the 45 tilting frame, slide-bars moving in such groove and secured to a frame, and extension-bars pivoted at their lower ends, respectively, to the grooved bar and the slide-bar and at their upper ends to the side bar of the 50 seat-frame, as shown, so that by moving the frame to which the slide-bars are attached the seat-frame may be elevated or lowered.

EDWIN PYNCHON.
